JAW CRUSHER

Einar H. Anderson, La Grange Park, Ill.

Application August 4, 1950, Serial No. 177,751

9 Claims. (Cl. 241—140)

1

This invention relates to an improvement in jaw crushers.

It has for one purpose to provide a compact strong and relatively light jaw crusher structure.

Another purpose is to provide a jaw structure in which the lateral component of movement of a moving jaw increases progressively from top to bottom of the crushing cavity.

Another purpose is to provide a jaw crusher in which a single moving jaw structure operates in compression with two normally fixed jaws.

Another purpose is to provide improved means for controlling or permitting the movement of the upper end of an oscillated jaw.

Another purpose is to provide an improved crusher frame for jaw crushers.

Another purpose is to provide improved feeding means for jaw crushers.

Another purpose is to provide improved release means for the normally fixed jaws of jaw crushers.

Another purpose is to provide improved mounting means for the normally fixed jaws of jaw crushers.

Other purposes will appear from time to time in the course of the specification and claims.

The invention is illustrated more or less diagrammatically in the accompanying drawings, wherein:

Fig. 1 is an end view with parts broken away and parts in section;

Fig. 2 is a section on the line 2—2 of Fig. 1;

Fig. 3 is a partial plan view of a variant form;

Fig. 4 is a section on the line 4—4 of Fig. 3 with the end cover plate removed;

Fig. 5 is a plan view with parts broken away illustrating a further variant form;

Fig. 6 is a section on the line 6—6 of Fig. 5 and including a diagrammatic showing of the movement of the moving jaw;

Fig. 7 is a partial side elevation of a variant form; and

Fig. 8 is a section on the line 8—8 of Fig. 7.

Like parts are indicated by like symbols throughout the specification and drawings.

Referring to the drawings, and first to the form of Figs. 1 and 2, any suitable base 1 may be employed upon which are supported side plates 2, 2, each such plate being shown as having an outwardly extending bottom flange 3 which may be bolted or otherwise secured to the base or foundation 1. 4, 4, indicate top flanges extending outwardly from the upper edges of the side plates 2 and illustrated as welded to the side plates. Extending across the space between the side plates is a structural member having a top wall 5, transversely extending side walls 6, and opposed bottom walls 7 extending toward each other from the lower edges of the side wall 6, but separated by a substantial opening or gap 8. 30

2

The said structural member may be welded or otherwise secured to the side plates 2. The above mentioned structural member may be open at the ends, the ends being closed by any suitable closure plates 9 which may be removed when access is necessary. The plates, however, may normally be held by suitable bolts 10. The side plates are also connected by a plurality of transversely extending members to which various parts of the closure may be secured. 12, 12a indicate the uppermost of a rather massive bar which may be welded or otherwise secured at its ends to the side plates 2. The upper inner end of each of the members 12, 12a has a bearing or supporting surface 12b which is generally semi-cylindrical. They are also apertured as at 12c for a purpose which will later appear, there being, for example, two of these apertures in each of the bars 12, 12a. Positioned at a lower level between the side plates 2 are transversely extending members 14a, 14a each of which has an upper member 14b and a lower member 14c, the members closed at the rear as by a plate or portion 14d. Between the upper and lower members 14b and 14c extends a sliding bar or member 15, which is normally forwardly thrust by a plurality of mass of springs 16 compressed between the members 14d and 15 and controlled by the adjustable tension or limit member 17 with its adjusting nut 17a. It will be understood that a substantial member of springs 16 may be employed, it being essential that they are of sufficient strength normally to hold the bar 15 in the advanced position in which it is shown at the right of Fig. 2.

I illustrate two normally fixed jaw elements 18, 18a. At the right side of Fig. 2, fixed jaw element 18 is shown as abutting against a supporting jaw structure 19. This jaw structure or plate has a top rearwardly extending portion 20 having a semi-cylindrical bearing surface conforming generally to the convex surface 12b of the transverse bar 12. The jaw support 19 is normally urged against the semi-cylindrical edge of the member 12, for example, by any suitable tension member 21 extending through an aperture 12c and yieldingly held by the spring 22. The lower edge of the jaw structure 19 is normally held in the position in which it is shown in Fig. 2 by the compression bar 25 which has a generally cylindrical enlargement 25a at each edge. One of these enlargements engages a bearing block or portion 26 on the jaw structure 19 while the other engages a bearing bar or member 27 which bears against the forward surface of the bar 15 or is shimmed adjustably in relation to it by the shims 28. It will be understood that under normal conditions, the above described supports will hold the jaw plate 18 in the position in which it is shown at the right of Fig. 2.

The opposite jaw plate 18a is shown as somewhat differentiated from the composite jaw structure 18, 19 at the right-hand side of the Fig. 2. It is a matter of choice whether the composite jaw is used or the simple jaw structure shown at the left. In order to keep the lower edge of the jaw normally compressed against the compression element 25, I illustrate in connection with the jaw structure 18, 19, a plurality of links of eyebolts 30 which pass through brackets 31 shown as mounted on the cross members 14a. The brackets are urged by the suitable springs 32 and adjustable washers 33 to hold the jaw structures firmly against the compression members 25. It will be understood that the compression members are in the form of bars which extend substantially across the jaw crushing structure. In connection with each jaw, I provide at least one dash-pot structure in the form of a cylinder 35 pivoted as at 36 to suitable ears or brackets 37 on the cross members 14a. Within the dash-pot cylinder is a piston 38 connected to the piston rod 39 pivoted as at 40 to the jaw structure. The piston 38 is shown as provided with a constantly open bleeder passage 41 of relatively small diameter and with a controlled and considerably larger passage 42 with its appropriate valve 43. It will be understood that the details of the dash-pot structure do not of themselves form part of the present invention, but that it is adapted to permit a rapid recession of the jaw structure, against the springs 16, in response to either the passage of uncrushable material through the crushing cavity, or the presence of an uncrushable mass in the crushing cavity. However, once the jaw has receded to the release position, compressing the springs 16, then the small diameter of the bleeder passage 41 permits only a slow return of the jaw toward its normal crushing position.

I illustrate between the two normally fixed but releasable jaws a unitary double-faced movable jaw structure. The jaw structure is shown as including a housing or sleeve 50, a top transverse portion 51 and connecting side plates 52 which extend substantially entirely across the crusher. Any suitable intermediate or end flanges 53 may also be employed. The side plates are shown as having upwardly and outwardly inclined ledges or over-hanging receiving flanges 54, the purpose of which will later appear. The transverse top portion of the jaw 51 has opposite generally semi-cylindrical recesses 55 which receives centering toggles 56 in the form of toggle bars which extend substantially across the crusher and have at their opposite edges generally cylindrical enlargements 56a and 56b which enter corresponding mating cavities in the abutment blocks or bars 57, 57a. The toggle bars may be urged toward each other by the provision of one or more springs 58. It will be understood that a snug fit is thus provided but the upper portion of the jaw is permitted a degree of tilt sufficient to allow it to take a normal crushing oscillation or movement. The actual crushing movement is imparted by any suitable eccentric 60 on a drive shaft 61, the drive shaft being driven, for example, by a pulley 62 from any suitable source of power, not herein shown. 63 indicates any suitable bearing structure between the hub 59 of the jaw and the drive shaft 61; the details of such bearing structure do not, of themselves, form a part of the present invention and are, therefore, not indicated.

Mounted on the opposite face of the jaw and against the plate 52 are the removable, replaceable jaw plates 65. Each such plate has its edges formed to enter and conform to the space above

the ledges 54. They may then be locked together by any suitable top clamping bars 66 drawn together by any suitable compression member 67. The crushing cavity defined between the opposed jaw members is completed by suitable removable wear plates 70, 71, the details of which do not form part of the present invention. They may be mounted by suitable bolts or securing member 72. Additional transversely extending hopper members 73 bridge the space between the side plates 2 and terminate at the lower edges at, or just above, the upper edges of the normal fixed jaw structure. I find it advantageous to provide a top feeding and feed confining box, generally indicated as 80, and having a top feed aperture 81 which overlies any suitable wear plate or removable wear member 82 positioned upon the transversely engaging structure member 5, 6, 7. The aperture 81 is shown in the form of a feeding slot extending substantially from side to side of the crusher and overlying the member 82.

In the form of Figs. 3 and 4, I illustrate a variant support for the upper end of the jaw structure. The jaw structure is generally indicated as 100. 101 indicates a transversely extending shaft which passes through a bore 102 in the upper end of the jaw structure 100. The shaft 101 has outer ends 103, extending into supporting boxes having upper ends 104 and lower members 105. These may be in the form of flanges secured to and outwardly extending from the crusher side plates 2a. The sides of the box are completed by end members 105 secured, for example, by bolts 106. Within the box thus formed are compression receiving members 107, 107, which are channelled as at 108 to receive the semi-cylindrical outer edges of the compression bars or toggles 109, the other ends of which extend into and conform to generally hemispherical channels 110 in the outer end portions 103 of the shaft 101. Members 107 are urged toward each other by any suitable spring elements 111. Any suitable shim 112 may be employed for the purposes of adjustment. It may be understood that the structure above described operates substantially like the corresponding structure of Figs. 1 and 2, but that the supporting structure for the upper end of the jaw is thus situated exteriorly of the side plates 2a and is readily accessible to the operator for the purpose of cleaning, repair or replacement. A removable closure plate 115 may be employed, as shown in Fig. 3. In the form of Fig. 4, I also illustrate a modification for the support of the upper edges of the normally fixed jaws. Each such jaw 120 has a generally semi-cylindrical socket portion 121 opposed to a generally cylindrical rod or enlargement 122 mounted on any suitable base or support 123. The upper edge of the jaw is yieldingly held in the position in which it is shown in Fig. 4 by any suitable compression member 124 and its associated spring 125.

Referring to the form of Figs. 5 and 6, I illustrate a link support for the upper end of the jaw as follows: The jaw structure which I indicate generally as 150 is apertured as at 151 to receive a shaft 152. This shaft has outwardly extending ends 153 which extend through appropriate elongated apertures 154 in the side plates 2b. Links 155 have eyes 156 which surround the outer ends 153 of the shaft 152. These links at their opposite ends have eyes 157 which surround stubs 158 which are suitably secured to side plates 2b. Thus, with reference to the structure shown in Fig. 6, the links 155 oscillate

slightly about a fixed center X. They are connected by the jaw structure as at the center Y. The jaw structure is rotated by rotation of the eccentric 161 on any suitably driven shaft 160. With the employment of the fixed center X and the moving center Y, the result of the rotation of the eccentric 161 is to impart a movement to the opposite faces of the jaw 150 which is diagrammatically indicated by the ovals spaced along the moving jaw faces of Fig. 6. It will be observed from Fig. 6 that these ovals flatten progressively from bottom to top of the crushing cavity. Also, the axis or long extension of the ovals departs increasingly from the horizontal toward the vertical, from the bottom of the crushing cavity to the top. The characteristic movement of the lower edge portion of the oscillated jaw structure has a lateral component of movement or an amplitude of lateral movement greatly in excess of the lateral amplitude of movement at the top of the cavity. In other words, the lower part of the moving jaw moves toward and away from the opposite and normally fixed jaw with a substantial travel, whereas the completed movement of the moving jaw toward and away from the fixed jaw progressively diminishes upwardly in the crushing cavity. At the top of the crushing cavity there is a very small amplitude of crushing movement.

In the form of Figs. 5 and 6, I illustrate also a somewhat different type of fixed jaw structure. I illustrate, for example, a normally fixed jaw 170 which has an upper hub 171 about a transversely extending supporting shaft 172. Transversely extending frame elements 173, 174 define a space in which a compression receiving bar 175 may be adjusted by shims or wedges 176. Springs may also be employed, if desired. 177 is a compression bar having semi-cylindrical edges which are shown as penetrating correspondingly formed apertures in the bar 175 and in lower portion 178 of the jaw 170.

Fig. 7 illustrates a form in which the jaw structure, generally indicated as 200, includes a top shaft 201 extending through a slightly elongated opening 202 in the side frame member 2b. The outwardly extending ends of the shafts 201 are positioned between cylindrical elements 203 mounted on retaining members 204. The members 203 may be made rotatable, if desired, about the supporting or centering members 204. In any event, the proportions, shapes and clearances of the various parts are such that the shaft 201, and thus the upper end of the jaw structure 200, is constrained to generally upright movement as the jaw is actuated or gyrated. It will be understood that if Fig. 7 were completed it would illustrate an actuating eccentric such as is shown at 60 in Fig. 2.

It will be realized that whereas I have described and claimed a practical and operative device, nevertheless, many changes may be made in size, shape, number and disposition of parts without departing from the spirit of my invention. I therefore wish my description and drawings to be taken as in a broad sense illustrative or diagrammatic, rather than as limiting me to my specific showing herein.

The use and operation of my invention are as follows:

I illustrate a multiple jaw crusher in which a single moving jaw element is oscillated by the rotation of an eccentric located adjacent the lower portion of the jaw.

The movement of the upper end of the jaw 75

structure may be controlled by oscillating compression bars as in the form of Figs. 1 to 4, or by a suitable linkage as shown in Figs. 5 and 6.

It is characteristic of my invention that I provide an oscillated jaw which has a differential movement from top to bottom, with a lateral amplitude of movement which increases from the top to bottom of the cavity. Thus, at the top of the cavity the amplitude of movement of the moving jaw toward the fixed jaw in the course of the crushing excursion is relatively slight. This amplitude increases downwardly toward the discharged end of the crushing cavity.

I illustrate a compact and light structure which is nonetheless strong and efficient and which occupies a minimum of space. It may be advantageously used, for example, in portable crusher plants, since it has a larger capacity in relation to its cubic content. I show an improved release means for the normally fixed jaws. As shown, for example, in Figs. 1 and 2, if uncrushable material, such as tramp iron, dipper teeth and the like enter the crushing cavity, the jaws 18 may quickly recede sufficiently either to permit the uncrushable material to pass through or at least to relieve the crushing stress. However, while the above-described dash-pot structure provides a rapid recession of the jaw, it is effective to permit only a relatively slow return of the jaw toward normal crushing position.

Thus, the machine cannot be subjected to the violent shock and risk of breakage which will take place in the event an uncrushable mass is located in the crushing cavity.

Although I illustrate different structures for controlling the movement of the upper end of the jaw, they all have, with the one exception below pointed out, the characteristic that they constrain the upper end of the jaw to a substantially vertical movement. However, with reference to Fig. 6, if the horizontal link 155 were downwardly inclined, as shown in the alternative indicated in the dot-and-dash line of Fig. 6, then a differential movement is provided for the opposite sides or faces of a moving jaw, and the upper end of the moving jaw moves at an angle to the vertical. The diagrammatic view of the movement of the jaw in Fig. 6 applies when the link 155 is in the horizontal position, whereas a different stroke will result if the downwardly inclined link is used. The same frame can carry stubs 158 in both the upper and the lower position of Fig. 6.

I claim:

1. In a double jaw crusher, a frame including parallel, upright side plates, two opposably facing, normally fixed jaws mounted on said frame and between said side plates, means for normally holding them in a predetermined position in relation to the frame, a pitman mounted between the jaws, the pitman having jaw plates opposed to each such fixed jaw and defining with the fixed jaws a pair of crushing cavities the ends of which are closed by the side plates, means for imparting bodily movement to the pitman including an eccentric mounted on the frame, means for rotating it about an axis lying in a horizontal plane extending through the pitman and the frame side plates, and including supporting connections for the upper end of the pitman extending outwardly of the crushing cavity, and outwardly beyond the side plates, opposed toggle elements movably mounted exteriorly of the frame side plates, and outside of and out of vertical alignment with the crushing cavities and

engaging opposed sides of said supporting connections, exteriorly of said side plates, said crushing cavities being upwardly open, and the upper end of the pitman, between the side plates, being upwardly exposed at all positions of its movement.

2. The structure of claim 1 characterized in that yielding supporting means is provided for at least one of the toggle elements, at each side of the frame, adapted to allow its endwise movement in response to up and down movement of the pitman.

3. The structure of claim 1 characterized in that all toggle elements, at each side of the frame, enter a common plane on each up or down stroke 15 of the pitman.

4. In a double jaw crusher, a frame having spaced, generally parallel side frame members, two opposably facing, normally fixed jaws mounted on said frame between said side members, means for holding them normally in a predetermined fixed position, while permitting their movement in response to predetermined excess crushing stress, a pitman mounted between the jaws, the pitman being generally triangular in vertical cross-section in a plane extending longitudinally of the crusher, jaw plates on said pitman opposed to each said normally fixed jaw, means for imparting bodily movement to said pitman including an eccentric mounted on the frame for rotation about an axis lying in a horizontal plane extending through the pitman in the sides of the frame but closely adjacent the bottoms of the cavities defined between the jaws and plates, the plates and jaws at each side of the pitman being of generally the same height and contour, and means for movably supporting the upper end of the pitman and for permitting a movement of the pitman having both vertical and horizontal components, said means including a shaft having outer ends extending outwardly through the side frame members, and transversely extending toggle members, exterior to said side frame members, each said toggle member being pivoted at one end to an outer end of said shaft, and abutments for the opposite ends of said toggle members.

5. The structure of claim 4 characterized in that yielding means are provided for permitting the outward recession of at least one of said abutments at each side of the frame.

6. The structure of claim 4 characterized by and including supporting means for said abutments, located exterior to the side frame members, said abutments, for each end of the shaft, being arranged in opposed pairs, at least one abutment of each said pair being yieldably mounted for recession.

7. In a double jaw crusher adapted for a differential crushing movement, a frame including parallel, upright side plates, two oppositely facing, normally fixed jaws mounted on said frame and between said side plates, means for normally holding them in a predetermined position in relation to the frame, a pitman mounted between the jaws, the pitman having jaw plates opposed to each such fixed jaw and defining with the fixed jaws a pair of crushing cavities, the ends of which are closed by the side plates, means for imparting bodily movement to the pitman, said 70 bodily movement in normal operation of the crusher increasing from top to bottom of the crushing cavities, including an eccentric mounted on the frame, means for rotating it about a horizontal axis extending through the pitman 75

and the frame side plates and located substantially below the top of the pitman, and including supporting connections for the upper end only of the pitman extending from the upper end of the pitman outwardly of the crushing cavity and outwardly beyond each of the side plates, movable connecting elements mounted exteriorly of the frame side plates, and outside of and out of vertical alignment with the crushing cavities and engaging opposed sides of said supporting connections for the upper end of the pitman, exteriorly of said side plates, said crushing cavities being upwardly open, and the upper end of the pitman between the side plates being upwardly exposed at all positions of its movement, the eccentric constituting the sole supporting connection for the lower end of the pitman, the movable connecting elements being formed and adapted normally to limit the amplitude of movement of the upper end of the pitman to less than the amplitude of movement imparted to the lower end of the pitman by the eccentric, whereby a differential movement is imparted to the pitman having a horizontal amplitude increasing from top to bottom of the crushing cavity.

8. The structure of claim 7 characterized by and including, as movable connecting elements for the upper end of the pitman, laterally extending links mounted exterior to the parallel side frame plates, each link being pivoted at one end in relation to an upper portion of the pitman and pivoted at the other end exteriorly of one of the side frame plates.

9. The structure of claim 7 characterized by and including, as movable connecting elements for the upper end of the pitman, laterally extending links mounted exterior to the parallel side frame plates, each link being pivoted at one end in relation to an upper portion of the pitman and pivoted at the other end exteriorly of one of the side frame plates, said links being pivoted in relation to the outer faces of said side frame plates at points lying in a plane below the plane of connection of said links to the upper end of the pitman.

EINAR H. ANDERSON.
